UNITED STATES PATENT OFFICE.

ISAAC N. LEWIS, OF MONTCLAIR, NEW JERSEY.

METHOD OF OPERATING FIREARMS.

Application filed November 23, 1918. Serial No. 263,823.

To all whom it may concern:

Be it known that I, ISAAC NEWTON LEWIS, a citizen of the United States of America, residing at 1 Russell Terrace, Montclair, 5 in the county of Essex and State of New Jersey, have invented certain new and useful Improvements in Methods of Operating Firearms, of which the following is a specification.

10 This invention relates to firearms, and particularly to automatic or semi-automatic firearms in which the gases of discharge resulting from the firing of a powder charge are employed for the purpose of causing operation of the actuating mechanism of the 15 firearm.

The primary object of the present invention is to provide in an automatic or semi-automatic firearm, a novel method of utilizing 20 the gases of discharge to effect an automatic or semi-automatic operation of the said actuating mechanism. Other objects of the invention are to provide for the employment of the gases of discharge in a 25 novel manner to effect an air cooling of the barrel, and if desired, of the actuating mechanism of the firearm, and to provide for the utilization of said gases for the purpose of reducing or neutralizing the recoil 30 of the firearm following the explosion of the powder charge.

The invention primarily consists in utilizing the gases of discharge resulting from the firing of a powder charge in the firearm 35 to produce a shock or very rapid pressure impulse, which is transmitted to the actuating mechanism of the firearm to cause operation thereof.

The production of the said shock or rapid 40 pressure impulse may be effected by checking or retarding the movement of the gases of discharge which flow from the muzzle end of the gun barrel following the discharge of the bullet therefrom. The forward movement of the gases is extremely 45 rapid and by the arrangement in the path of the gases, of means for momentarily checking or retarding such movement thereof, a sudden pressure impulse or shock is produced when the gases come into contact with 50 said means, which impulse or shock may be transmitted backwardly to the actuating mechanism of the firearm and is of sufficient energy to cause operation of the same. Alternatively the shock or pressure impulse 55

may be produced by checking or retarding the free expansion of the discharge gases, as will be more fully referred to hereinafter.

An important distinction must be drawn at the outset between the present method 60 of automatic or semi-automatic operation of a firearm by shocks or pressure impulses, and the method of automatic operation involving the direct pressure of the heated gases of discharge upon parts connected 65 with the actuating mechanism of the firearm. In the improved method the hot gases of discharge do not necessarily come into direct contact with the actuating mechanism or parts connected thereto to transmit the 70 shocks or impulses, as such shocks or impulses may be, and preferably are transmitted to said mechanism, or said parts, through the medium of an intervening column of air. Thus said mechanism, or said 75 parts, do not become highly heated by the gases and do not become fouled by deposits therefrom, enabling the firearm to be operated for more extended periods without cleaning, and preventing jamming or inefficient operation due to said fouling deposits. Furthermore, as the shock or impulse is produced and transmitted to the actuating 80 mechanism practically instantaneously with the discharge of the bullet from the barrel, 85 the speed of operation is increased when firing entirely automatically, and a greater number of bullets may be discharged in any given interval.

The invention also consists in utilizing 90 the gases of discharge to produce a shock or very rapid pressure impulse, and utilizing said shock or pressure impulse to effect a circulation of cooling air over or around the barrel, and if desired, over the actuating 95 mechanism of the gun.

The invention further consists in utilizing the gases of discharge to produce a shock or very rapid pressure impulse, of such a nature as to reduce or neutralize the recoil 100 of the firearm due to the explosion of the powder charge.

Other features of the invention will be more fully described hereinafter and particularly pointed out in the appended 105 claims.

In the accompanying drawings, for the purpose of illustration only, and without any intention of limiting the invention to any particular construction or type of fire- 110

arm, is shown a machine or rapid fire gun adapted to be operated automatically or semi-automatically in accordance with the improved method of operation.

5 In these drawings:—

Figure 1 is a longitudinal sectional view of the body or receiver of the gun and parts carried by or working within the same, the operating parts being shown in substantially 10 the rearmost positions to which they are moved by the shock-operated means;

Figure 2 is a similar view but showing the operating parts in the positions they occupy at the instant of firing;

15 Figure 3 is a longitudinal sectional view of the forward portion of the gun showing one form of means for producing the shocks or rapid pressure impulses, and means for transmitting the shocks or impulses to the actuating mechanism of the gun, the latter means being shown in position corresponding 20 to that of the parts in Figure 2, and

Figures 4, 5 and 6 are cross-sectional views taken on the lines 4—4, 5—5 and 6—6 respectively of Figures 1 and 3.

In one form the means for utilizing the gases of discharge to produce the shock comprise a chamber and a piston member movable within the said chamber, the movement of the piston member being transmitted to the actuating mechanism of the firearm. The said chamber is formed between the gun barrel and a casing surrounding the latter along its entire length and 35 extending forwards in front of the muzzle end thereof. At its forward end the wall of the casing is turned inwards forming an inwardly projecting flange having a central aperture or mouth of slightly greater diameter than that of the bullet. This arrangement permits the free passage of the bullet. When the rear end of the bullet has left the muzzle end of the gun barrel and during the small fraction of a second the bullet 40 takes to pass through the aperture in the end of the casing, the discharge gases expand within the chamber transmitting a wave of high pressure through the air within the chamber, thereby driving the piston member backwards and operating the actuating mechanism of the gun. When the rear end of the bullet has left the mouth of the casing the confined gases in the chamber and inside the gun barrel can issue freely 50 through the mouth of the casing. The gases still at high pressure within the gun barrel issue from the muzzle thereof and expand with great turbulence within the chamber simultaneously with the escape of gases 55 through the mouth of the casing. During the initial part of this period the pressure wave transmitted rearwardly inside the chamber to the piston member is increasing 60 in intensity and finally reaches a maximum. The maximum pressure on the piston is suc-

ceeded by a fall of pressure, the gases issuing from the mouth of the casing with sufficient kinetic energy to induce a partial vacuum within the chamber and gun barrel. Meantime the piston member is still moving rearwards and may be made to uncover a passage formed by an enlargement of the diameter of the wall of the casing. A free passage is then provided inside the casing from the rear end thereof to its mouth. 70 Fresh cold air enters the chamber through inlet ports near the rear end of the casing, and a powerful draught is induced by the kinetic energy of the gases still issuing from the mouth of the casing. 75

The pressure and kinetic energy transmitted to the piston member is employed partly in effecting the backward stroke of the actuating mechanism and partly in energizing a "return spring" which is caused to 80 effect the forward or return stroke of the actuating mechanism.

It is to be particularly observed that the velocity of the gases issuing from the mouth of the casing is that due to the head or pressure within that portion of the chamber between the muzzle end of the barrel and the mouth of the casing. This pressure varies rapidly but its maximum and average values are much less than the corresponding values 90 in the case of discharge gases issuing from the muzzle of a gun of ordinary construction. In the latter the maximum velocity of efflux of the discharge gases is of the order 10,000 feet per second; with the expansion in the chamber provided by the present invention, the maximum velocity of efflux of the discharge gases is considerably less. Accordingly, the velocity and momentum of 95 the discharge gases and therefore also the 100 momentum of recoil of the gun, are all greatly reduced by the present invention, and also the rapidly moving discharge gases as they impinge upon the shock producing 105 obstruction in their path partially neutralize 110 and materially lessen the free recoil of the arm.

Referring more in detail to these drawings, it will be noticed that the barrel 1 at its rear or breech end has a screw-threaded 115 connection at 2 with the forward or breech end of the body or receiver 3. Surrounding the barrel 1 throughout its entire length is a casing 4 which at its rear end is mounted upon the forward end of the body 3 and is 120 securely connected thereto by any suitable means. The particular means shown comprises a split band 5 fitting around the forward end of the body portion and the rear end of the casing and co-acting with flanges 125 or shoulders 6 projecting from said ends, the lower ends of the band being drawn together, to tightly grip the body and casing and securely connect the same together, by means of a nut 7 engaging screw-threads 130

and conical surfaces on the ends of the band. The particular connecting means is however immaterial so far as the present invention is concerned.

5 The casing 4 at its forward portion is reduced in size so that it is of greater diameter than, but concentric with the barrel 1, and at its extreme forward end the casing extends some distance beyond the forward 10 or muzzle end of the gun barrel. In this particular adaptation of the invention this forward portion of the casing constitutes the means for producing the shocks or rapid pressure impulses, and it may be formed in 15 various ways in order to produce said shocks or impulses. Thus as illustrated in Figure 3, the casing wall at its forward end is turned inwardly, as shown at 8, to produce an inwardly extending flange forming in effect an apertured forward wall on the casing, which permits the passage of the bullet and the subsequent retarded escape of the gases of discharge. As the gases of discharge flowing freely from the muzzle end 25 of the barrel, following the discharge of the bullet therefrom, come into contact with the apertured forward wall 8 of the said casing or chamber, the consequent momentary check or retardation of the gases causes the production of the aforesaid shock or backward 30 pressure impulse, and this shock or impulse may be transmitted backwardly to the actuating mechanism by suitable means, as hereinafter referred to. By regulating the size 35 of the aperture in the forward wall 8 of the casing 4, or the distance of said wall from the muzzle end of the gun barrel 1, or by suitably proportioning the size of the aperture and the distance between the wall and 40 muzzle end of the gun barrel, a pressure impulse or shock may be produced of such energy as to effect operation of the actuating mechanism in the most satisfactory and efficient manner. The regulation of the size 45 of the aperture and its distance from the end of the barrel permits the energy of the shock or impulse to be determinated with extreme accuracy, whereby the actuating mechanism may be operated with great nicety and 50 smoothness and without imparting unnecessary shocks to the same or otherwise straining the parts of the gun.

The forward portion of the casing 4 terminating in the apertured end wall 8, may be 55 of cylindrical form, so that the shock or impulse is produced entirely by the contact of the rapidly moving gases with the said apertured wall, or as shown in Figure 3, said portion may be of slightly conical or tapered form, the conical or tapering wall of 60 said portion cooperating with the apertured end wall in producing the shock or impulse.

Alternatively the checking or retarding of the gases of discharge may be effected entirely by tapering the wall of the forward

portion of the casing 4, the extreme forward end of the casing being open, and the forward movement of the gases being checked or retarded due to the passage of said gases through the chamber of gradually reducing 70 cross-section formed by the tapering wall of the casing. It will be clear that in this case also, by regulating the size of the aperture at the forward end of the casing or by regulating the distance of said aperture from 75 the muzzle end of the barrel, or by suitably proportioning the size of the aperture and the distance of the same from said muzzle end, the energy of the shock or impulse produced may be accurately controlled. Further, the checking or retarding of the gases might be effected by the use of a forward 80 casing portion of cylindrical form having its extreme forward end open by so determining the internal diameter of said portion 85 that the free expansion of the gases of discharge from the muzzle end of the gun barrel into the chamber formed by said casing portion is momentarily checked as the bullet 90 is discharged.

The forward portion of the casing 4, in the firearm illustrated, is supported by means of a spider support 9, consisting of a cylindrical sleeve fitting onto the cylindrical portion 10 at the muzzle end of the gun barrel, 95 and provided with radial arms or fins 11 engaging the interior of the casing 4 at their outer edges, some or all of said arms or fins extending rearwardly beyond the rear end of the sleeve, as illustrated in Figure 3. 100

The shocks or impulses produced by the above described regulation of the discharge gases, may be transmitted to the actuating mechanism of the firearm through the medium of a piston working in a suitable cylinder, which piston is connected by a rod or other convenient means to the bolt or other part of the actuating mechanism. In the particular construction shown in the drawings, the piston 13 is of annular form and is 105 arranged to reciprocate upon a cylindrical portion 12 of the gun barrel, and to fit within the annular space between this portion and the interior surface of the adjacent concentric portion of the casing 4, this piston 110 member at its rear end being formed with a radial extension 14 to which is connected, as by means of screw-threads 15, the forward end of a piston rod or connecting rod 16. This rod extends rearwardly in the enlarged 115 portion of the casing 4 and into the body or receiver 3, where it is connected to the cylindrical operating member 17, slidable within the upper cylindrical way or bore of said body. The space in front of the piston is in 120 free communication with the forward portion of the casing 4 in front of the gun barrel, so that a column of air is always maintained in front of the piston. On the firing 125 of a cartridge or powder charge, the shock or 130

backward pressure impulse produced by the aforesaid novel utilization of the discharge gases, is transmitted to the column of air in front of the piston 13, and by said column to the piston itself, the latter being thereby moved rearwardly so as to actuate the said operating member 17.

The actuating mechanism of the firearm illustrated is located within the body 3 and comprises the operating member 17, slideable within the upper bore of said body; the hollow cylindrical breech block or bolt 18 slidably arranged in the lower way or bore of the body 3, and the firing pin 19 slideable within said bolt. The operating member effects both rotational and reciprocating movements of the bolt 18, by means of the post 20 depending from said operating member and co-acting with a cam slot 21 in the bolt, said post also effecting movement of the firing pin 19 within the bolt. The return spring 22 surrounds an extension 23 of the operating member and bears at its rear end against the butt-stock 24.

When the bolt is released, as hereinafter described, the return spring 22 moves the operating member 17 forwardly and carries with it the bolt 18, the post 20 engaging an inclined part of the cam slot in the bolt and the latter being prevented from rotating by a projection 25 engaging the slot 25^a between the upper and lower bores of the body 3. When the forward end of the bolt engages the breech end of the barrel 1, having forced a cartridge in advance of it into the chambered end of the barrel, the projection 25 is freed from the slot 25^a and the bolt is rotated, by the post 20 co-acting with the inclined portion of the cam slot 21, to bring the lugs 27 on the bolt in front of the lugs 28 in the body 3 to prevent rearward movement of the bolt by the firing of the cartridge. The operating member after such rotation moves into the position indicated in Figure 2, and moves the firing pin 19 into position to strike the head of the cartridge and fire the same. The discharge gases, following the bullet thus discharged, issue from the muzzle end of the gun into the forward portion of casing 4, and the shock or rapid pressure impulse produced in the manner previously referred to is transmitted through the intervening column of air to the piston 13 and causes the latter to move rearwardly on the portion 12 of the barrel, the rod 16 during such movement forcing the operating member 17 rearwardly. Said member on its initial movement unlocks the bolt 18 by rotating it in the reverse direction and then carries the bolt rearwardly, against the action of the return spring, energizing the latter in order that it may effect a succeeding forward movement of the parts.

The said actuating mechanism, after operation thereof by the aforesaid shock or

pressure impulse, may be restrained from further operation until manipulated by the user or operator of the firearm, in which event said actuating mechanism will be manipulable to cause the firing of individual rounds and will be re-energized by the shock or impulse produced at each explosion of a cartridge. Or said actuating mechanism may be of such a nature, or so manipulable, that it is not restrained after each discharge of a bullet, in which event any desired number of cartridges, or the full number of cartridges in the magazine may be successively exploded. With this arrangement the shock or pressure impulse produced by the novel utilization of the gases of discharge of the first cartridge or shell exploded is caused, in the manner described, to energize the actuating mechanism of the firearm so that it will immediately operate to fire the succeeding cartridge or shell operatively positioned with respect to said mechanism, the gases of discharge produced at each explosion of a cartridge or shell thereafter energizing the actuating mechanism to fire the succeeding cartridge or shell until the desired number has been fired, or the magazine emptied.

These results may be accomplished by the use of the trigger mechanism illustrated in Figs. 1 and 2, and which comprises the guard 25' slidably fitted to the lower portion of the body 3, the trigger 26 being pivoted in a recess in this guard and having a shoulder 26^a adapted to co-act with the forward end of the pivoted sear 27^a, the rear end of which is adapted to engage a notch 28^a in the rear end of the bolt 18 to restrain the same against the pressure of the return spring.

With the trigger and sear in the relative positions indicated in Figure 1, the shoulder 26^a of the trigger when the latter is pressed will engage and raise the forward end of the sear, lowering the rear end thereof from the notch 28^a in the bolt and permitting the latter to be actuated by the spring 22. The shoulder 26^a then snaps past the end of the sear and the latter under the action of its spring resumes its initial position ready to engage and hold the bolt when the latter is returned by the shock or pressure impulse produced. The trigger pin 29 however is eccentrically mounted in the guard 25' and when it is rotated in a clockwise direction by means of handle 30, the trigger is permitted to move rearwardly so that the shoulder 26^a moves farther beneath the forward end of the sear. Thus when the trigger is pressed, the shoulder 26^a actuates the sear to release the bolt as above described, but cannot snap past the end of the sear and holds the latter in inoperative position. The bolt then on its return movement is not held by the sear, but when it has moved rearwardly sufficiently to clear the head of the succeeding cartridge, it is again pressed

forwardly by the spring 22, the operation being repeated until the trigger is released, or the magazine exhausted.

There is thus provided by the novel utilization of the discharge gases, a shock-operated automatic firearm, the actuating mechanism of which may be manipulated to fire individual cartridges, or to fire entirely by shock-operation, after the discharge of the first cartridge, any desired number thereof within the capacity of the magazine.

It will be noted that the rod 16 is connected to the operating member 17 by means of a charging handle 31, the flat portion 15 of which passes through slots in the member and rod and works in a longitudinal slot 32 in the body 3. By manual rearward operation of this handle 31, the operating member 17, bolt 18 and piston 13 may be 20 moved into the position shown in Figure 1 ready to fire a cartridge.

The cartridges in the particular gun illustrated are arranged in a magazine 32^a detachably mounted in a recess in the lower 25 part of the body 3 communicating with the lower bore thereof, the cartridge being fed upwardly by a follower 33 and spring 34 into position to be successively engaged by the forward end of the bolt and forced there- 30 by into the chambered end of the barrel 1. On the return movement of the bolt, the empty shell is withdrawn by the extractors 34^a carried by the bolt and at a predetermined instant, the bolt actuates ejector 35 mechanism to eject the shell through the ejection aperture 35 in the body 3. The ejector mechanism is not shown, and may be of any suitable character.

It will be understood that the shock or 40 impulse operated piston 13 in addition to serving to operate the actuating mechanism of the firearm, is so arranged that during its reciprocating movements it has a pumping effect on the air within the casing 4, and 45 by providing air inlets at suitable points in said casing, the piston when reciprocated will force the warm air from the casing and draw cooler air thereinto. Further, the piston 13 when at or near the rear end of 50 its stroke does not touch the wall of the casing at the enlarged portion 41. A clear passage for air is then provided inside the casing from the inlet ports 40 to the mouth. The discharge gases issuing from the mouth 55 of the casing induce a powerful draught, thus effecting a circulation of air between the casing and the gun barrel and effectively cooling the latter. If desired, the rod 16 may loosely fit within the forward portion 60 of the body, so that the piston 13 may circulate cooling air over the actuating mechanism of the firearm and within the body 3, for the purpose of maintaining said parts and body, in addition to the barrel, in cool 65 condition during operation of the firearm.

Or the gases of discharge may be otherwise utilized to produce said circulation of cooling air.

It will be readily understood that the aforesaid retardation or checking of the 70 movement or expansion of the discharge gases produces shocks or pressure impulses which serve to reduce or neutralize the recoil of the firearm due to the explosion of the cartridge so that the firearm may be 75 operated more easily and with greater accuracy.

As previously indicated, the essential feature of the invention is the method of automatically or semi-automatically operating a 80 firearm by means of shocks or pressure impulses caused or produced by a novel utilization of the gases of discharge. The invention is not restricted to any particular manner of producing these shocks or impulses, 85 although to enable the invention to be clearly understood, various ways in which the same may be produced have been described. Furthermore, it is particularly desired to point out that the invention is not 90 restricted to the use of the improved method of operation with firearms of any particular construction or size or calibre, as, although the invention may be particularly applicable to rifles or shoulder arms, and 95 for convenience has been illustrated as applied to such arms, it is also applicable as will be clearly understood by those skilled in the art, to firearms of other types or construction, and of smaller and larger size 100 or calibre. Further, the invention also extends to the methods of air cooling the parts of a firearm, and reducing the recoil of a firearm, by the use of shocks or pressure impulses as previously referred to.

Having now particularly described and ascertained the nature of my said invention and in what manner the same is to be performed, I declare that what I claim is:

1. The method of automatically operating 110 a firearm, which consists in acting upon the discharge gases to produce a shock or very rapid pressure impulse, and utilizing said shock or impulse to cause a subsequent operation of the firearm.

2. The method of automatically operating 115 a firearm, which consists in acting upon the discharge gases to produce a shock or very rapid pressure impulse, impressing said shock or impulse upon a column of air, and 120 utilizing said impressed shock or impulse to cause a subsequent operation of the firearm.

3. The method of automatically operating 125 a firearm, which consists in acting upon the discharge gases to produce a shock or very rapid pressure impulse, storing up the energy of said shock or impulse, and subsequently releasing said stored energy to cause operation of the firearm.

4. The method of automatically operating a firearm, which consists in momentarily checking the forward movement of the discharge gases to produce a shock or very rapid pressure impulse, and utilizing said shock or impulse to cause a subsequent operation of the firearm.
5. The method of automatically operating a firearm, which consists in momentarily 10 checking the expansion of the discharge gases issuing from the muzzle end of the barrel to produce a shock or very rapid pressure impulse, and utilizing said shock or impulse to cause a subsequent operation of 15 the firearm.
6. The method of automatically operating a firearm, which consists in producing a succession of shocks or very rapid pressure impulses by acting upon successive 20 charges of gas from the barrel of the arm, and utilizing said succession of shocks or impulses to cause repeated operation of the firearm.
7. The method of operating an automatic 25 firearm, which consists in acting upon the discharge gases to produce a shock or very rapid pressure impulse, and utilizing said shock or impulse to cause a circulation of air for cooling said arm.
- 30 8. The method of operating an automatic firearm, which consists in imparting to the stream of discharge gases issuing from the muzzle end of the gun barrel a momentary check uniformly about the axis of said barrel, and then permitting said gases to flow 35 forwardly without lateral deflection, to produce a shock or very rapid pressure impulse, for the purposes specified.
9. The method of automatically operating 40 a firearm, which consists in momentarily confining the expanding gases issuing from the muzzle end of the gun barrel within a space having its normal communication with the atmosphere momentarily restricted 45 by the passage of the bullet to produce a shock or compression wave, and utilizing the

energy of said shock or wave to cause a subsequent operation of the firearm.

10. The method of automatically operating a firearm, which consists in utilizing 50 the discharge gases to impose a shock or compression wave upon a relatively stationary mass of elastic fluid within a chamber in communication with the atmosphere, and utilizing said shock to cause a subsequent 55 operation of the firearm.

11. The method of automatically operating a firearm, which consists in expanding the discharge gases within a chamber in communication with the atmosphere to produce a shock of compression and rarefaction, and utilizing said shock to cause a subsequent 60 operation of the firearm.

12. The method of automatically operating a firearm, which consists in utilizing 65 the discharge gases to produce a shock of compression and rarefaction on a mass of air within a chamber in communication with the atmosphere, and utilizing said shock to create a draught of cooling air over and 70 around the barrel of the firearm.

13. The method of operating a firearm, which consists in acting upon the stream 75 of discharge gases issuing from the muzzle end of the gun barrel uniformly about the axis of the gas stream to momentarily check or confine said gases without causing lateral deflection thereof to produce a shock or very rapid pressure impulse, for the purposes specified.

14. The method of operating a firearm, which consists in acting upon the stream 80 of discharge gases issuing from the muzzle end of the gun barrel uniformly about the axis of said stream to produce a shock or very rapid pressure impulse and imparting 85 said shock or impulse to a body of elastic fluid disposed uniformly about the axis of the gas stream, for the purposes specified.

In testimony whereof I affix my signature. 90

ISAAC N. LEWIS.
